UNITED STATES PATENT OFFICE.

SAMUEL G. COLSON, OF ASHTON, IDAHO.

STEAM-ENGINE VALVE-GEAR.

1,136,893.

Specification of Letters Patent. Patented Apr. 20, 1915.

Application filed September 2, 1914. Serial No. 859,904.

To all whom it may concern:

Be it known that I, SAMUEL G. COLSON, a citizen of the United States, resident of Ashton, in the county of Fremont and State of Idaho, have made a certain new and useful invention in Steam-Engine Valve-Gear; and I declare the following to be a full, clear, and exact description of the same, such as will enable others skilled in the art to which it appertains to make and use the invention, reference being had to the accompanying drawings, and to letters or figures of reference marked thereon, which form a part of this specification.

Figure 1 is a longitudinal section of the invention taken on the line 1—1, Fig. 2. Fig. 2 is a plan view of the steam chest and cylinder with parts removed. Fig. 3 is a section on the line 3—3, Fig. 2, parts being broken away. Fig. 4 is a diagrammatic view in section, the section being taken circularly through the two sets of diametrically opposite lateral ports, and straightened out, an arrow showing the lead to start the engine and another arrow the exhaust. Fig. 5 is a detail plan view of the steam chest with top removed. Fig. 6 is a detail top plan view of the valve. Fig. 7 is a detail bottom plan view of the same. Fig. 8 is a section on the line 8—8, Fig. 7. Fig. 9 is a detail plan view of the reversing plate. Fig. 10 is a section on the line 10—10, Fig. 9.

The invention has relation to rotary valve gear for steam engines having a reciprocating piston, and it consists in the novel construction and combinations of parts, as hereinafter set forth.

In the accompanying drawings, illustrating the invention, the numeral 2 designates the top of the cylinder, and 3 a circular valve box, said top having therein a circular exhaust opening 5, located centrally and concentric of said box; said top having outer diametrically opposite steam ports 7, 7' and 8, 8', also concentric of said box, a port 7 and 8 being located adjacent to each other at each side of said box.

Fitting within the valve box, upon the top 50 of the cylinder, is the reversing disk or plate 8², having therein central approximately sector-form ports 9, 9', divided by partition 10, and diametrically opposite ports 11, 11', located near the edge of the plate and registering with either ports 7, 7' or 8, 8', ac-

cording to the adjustment of the reversing plate, which is operated by suitable means, usually a sliding rod or bar *a*, having rack teeth *b*, engaging arcuate rack teeth *c*, of the reversing plate, the ports 9, 9' being always 60 in register with the exhaust port 5 of the top of the steam chest.

Fitting upon the reversing plate, within the valve box, is the rotary valve plate 14, having therein an arcuate elongated steam port 15, of approximately ninety degrees in extent and located near the edge of the plate at one side thereof, the bottom of said plate having at the other side thereof a sector-form chamber 15', also of about ninety degrees measurement. This valve plate is designed to be turned by the shaft of the engine wheels, having a driving connection therewith, preferably by means of a shaft 16, operating said plate and operated by 70 chain connection 18 with the engine shaft.

Fitting upon the valve plate, in the valve box, is the cushion or top plate 19, having ports 20, 20' and 21, 21', corresponding in location and size with the ports 7, 7' and 8 80 8' of the top of the cylinder, this plate 19 being separated from the top of the steam chest to form a chamber 22, wherein steam is introduced suitably, as by pipe 23.

In operation, the reversing plate being in one position of adjustment, shown in Fig. 3 of the drawings, as the valve plate is turned, the steam in chamber 22 will enter through port 20'—then through port 15 of the valve plate—then through port 11' of the reversing plate, and finally through port 7' of the top of the cylinder, the last named port having communication by passage 24 with one end of the cylinder.

As the valve plate is turning to admit the steam to the end of the cylinder, as stated, the long opening of the port thereof will provide for an extended admission of the steam, determined by the length of the port, and while this port is passing in register with the other ports, as stated, the chamber 15' will bridge the ports 7, 5 of the top of the cylinder, bringing them into communication to establish the exhaust from the other end of the cylinder, through passage 25 laterally to the atmosphere.

As the valve plate continues to turn, the port 20' will be closed and steam cut off therefrom, the port 20 being then opened to admit steam thereto, from which it will pass 110

through the port of the valve plate, the port 11 of the reversing disk and through port 7 of the top of the cylinder, through passage 26 to the opposite end of the cylinder, 5 the chamber 15' at the same time bridging the ports 7', 5 to establish the exhaust, as previously stated for the ports 7, 5.

When the reversing plate is adjusted to opposite position the steam in chamber 22 10 will enter through port 21', then through port 15 of the valve plate, then through port 11' of the reversing plate, and finally through port 8' of the top of the cylinder, the last-named port having communication 15 by passage 26 with one end of the cylinder. And as the valve plate turns to admit steam to the end of the cylinder, as stated, the chamber 15' will bridge the ports 8, 5 of the top of the cylinder, to establish the exhaust from the other end of the cylinder, 20 through passage 25.

As the valve plate continues to turn, the port 21' will be closed and steam cut off therefrom, the port 21 being then opened to 25 admit steam thereto, from which it will pass through the port of the valve plate, the port 11 of the reversing disk, and through port 8 of the top of the cylinder, through passage 24 to the opposite end of the cylinder, the 30 chamber 15' at the same time bridging the ports 8', 5, to establish the exhaust.

In order to provide a steamtight joint for the valve under the conditions of ordinary shop practice, and to allow for wear, the 35 valve and reversing plate are designed to be mounted as follows: In the cylinder wall 2 is provided a journal seat 28, and the reversing plate is formed with a central hollow boss 29, designed for bearing engagement 40 with said seat. The valve plate 14 has an inner central bearing stud 30, registering with the hollow of said boss, and opposite this stud is provided with a prismatic seat 31, designed for loose, automatically adjustable engagement by a similarly formed end 32 of the driving shaft 16. The joints of 45 the interfitting parts are truly ground, and the top plate is bolted to the cylinder at 27, fixing the plates in their seats as an independent unit. The plates, being separate 50 from the driving means, will tend to adjust themselves in their seats, under steam pressure, whereby a close, steamtight joint is insured under all conditions.

What I claim is:

1. In valve gear for steam engines, the combination with an engine cylinder having steam ports communicating with opposite ends thereof, of a steam chest having two sets of diametrically opposite lateral ports, 60 the ports of each set communicating with opposite steam ports, an exhaust port in said chest, a rotary valve having at one side a long arcuate port and at the other side a long chamber to bridge successively the lateral ports and the exhaust port, a reversing plate having diametrically opposite ports adapted to register with either set of said lateral ports and to close the other set of 65 said ports, and means for rotatably mounting said valve and said plate, comprising a journal seated in the cylinder wall, a hollow boss upon said plate in register with said journal seat, a stud upon said valve engaging the hollow of said boss, a prismatic seat in said valve opposite said stud, and a driving shaft loosely engaging said prismatic seat. 70

2. In valve gear for steam engines, the combination with an engine cylinder having steam ports communicating with opposite ends thereof, of a steam chest having two sets of diametrically opposite lateral ports, 75 the ports of each set communicating with opposite steam ports, an exhaust port in said chest, a rotary valve having at one side a long arcuate port and at the other side a long chamber to bridge successively the lateral ports and the exhaust port, a reversing 80 plate having diametrically opposite ports adapted to register with either set of said lateral ports and to close the other set of said ports, and means for rotatably mounting said valve and said plate, comprising a journal seat in the cylinder wall, a hollow boss upon said plate in register with said journal seat, a stud upon said valve engaging the hollow of said boss, a prismatic seat in said valve opposite said stud, a driving 85 shaft loosely engaging said prismatic seat, and a retaining plate secured to said cylinder wall and engaging said valve. 90

In testimony whereof I affix my signature, in presence of two witnesses.

SAMUEL G. COLSON.
